UNITED STATES PATENT OFFICE

ANTON FAZEKAS, OF SAN FRANCISCO, CALIFORNIA

DESIGN FOR A HOUSE-NUMBER-PLATE

Application filed June 1, 1931. Serial No. 40,053. Term of patent 14 years.

To all whom it may concern:

Be it known that I, ANTON FAZEKAS, a citizen of the United States, residing in the city and county of San Francisco, State of California, have invented a new, original, and ornamental Design for a House-Number-Plate, of which the following is a specification, reference being had to the accompanying drawings, forming part thereof.

Fig. 1 is a front elevation showing my house-number-plate;

Fig. 2 is a plan view showing the same;

and

Fig. 3 is an end elevation showing the same.

I claim:

The ornamental design for a house-number-plate as shown.

ANTON FAZEKAS.
